UNITED STATES PATENT OFFICE.

ANDREW J. UPHAM, OF SYCAMORE, ILLINOIS, ASSIGNOR TO THE WASH-BURN & MOEN MANUFACTURING COMPANY, OF WORCESTER, MASSACHUSETTS, AND ISAAC L. ELLWOOD, OF DE KALB, ILLINOIS.

BARBED METAL-STRIP FENCING.

SPECIFICATION forming part of Letters Patent No. 272,923, dated February 27, 1883.

Application filed October 28, 1882. (No model.)

To all whom it may concern:

Be it known that I, ANDREW J. UPHAM, of Sycamore, in the county of De Kalb and State of Illinois, have invented certain new and useful Improvements in Barbed Metal-Strip Fencing; and I do hereby declare that the following is a full, clear, and exact description of the same, reference being had to the accompanying drawings, forming a part of this specification, and in which—

Figure 1 represents a view of a section of flat metal strip with my barbed fencing formed on one end thereof, as will be hereinafter fully described. Fig. 2 represents cross sections of the parts A and B, respectively, taken on line *a b*, Fig. 1, looking in the direction of the arrow, same figure; and Fig. 3 represents a section of a strip of metal, such as is used in making my improved fencing, in the manner to be hereinafter described, also showing on one end of said strip the mode of cutting the same to form two strips of sheet-metal fencing.

To enable those skilled in the art to which my invention belongs to make and use the same, I will proceed to describe it more in detail.

In the drawings, the part marked C, Fig. 3, represents a strip of thin metal, (also showing the mode,) from which two sections of my improved strip-fencing are cut by cutting or severing the strip C through its central portion in such a way as to leave the triangular parts D with pointed ends projecting from one edge of each section of fencing. The lines *cc* represent the cuts made in the strip C preparatory to forming the fencing. After the strip C has been cut in the manner above described

the parts D of each section of fence are bent or pressed back upon the body of the fence, and the pointed ends F then bent or turned up, so as to project out at right angles from the strip of fencing, as clearly shown in the part B, Fig. 1 of the drawings and in Fig. 2 of the drawings.

The part A, Fig. 1 of the drawings, shows a modification of my barbed metal-strip fencing, tacks E being inserted between the edges of the parts D. The fencing may then be drawn through a galvanizing-bath, thus securely fastening the tacks or headed pieces of metal, upon which the edges of the parts D press, in place upon the fencing-strip. By cutting two strips of fencing at the same time from the strip C in the manner above described there will be no waste of the fencing material. It will be observed that the ends F of the parts D are bent up about midway of said parts D, so as to rest for support upon the center portion of the strip, as shown in Fig. 2 of the drawings.

Having described my improvements in barbed metal-strip fencing, what I claim therein as new and of my invention, and desire to secure by Letters Patent, is—

A metal-strip fencing having one edge cut with triangular parts D, said parts being bent over upon the body of the strip and the ends F bent up about midway of the strip, and projecting out therefrom to form points or barbs, substantially as shown and described.

ANDREW J. UPHAM.
